UNITED STATES PATENT OFFICE.

CURTIS J. ROTHERMEL, OF PHILADELPHIA, PENNSYLVANIA, ASSIGNOR TO THE BARRETT COMPANY, A CORPORATION OF NEW JERSEY.

RETAINER MEMBER FOR ROOFING-FABRIC ROLLS.

1,312,211.

Specification of Letters Patent.

Patented Aug. 5, 1919.

Application filed May 19, 1917. Serial No. 169,788.

To all whom it may concern:

Be it known that I, CURTIS J. ROTHERMEL, a citizen of the United States, residing at Philadelphia, in the county of Philadelphia 5 and State of Pennsylvania, have invented certain new and useful Improvements in Retainer Members for Roofing-Fabric Rolls, of which the following is a specification.

The object of my invention is to provide 10 an improved means in the form of a retainer member for retaining and supporting within a roll of roofing or similar construction fabric or material, the packages of cement, nails, etc., to be used in securing the roofing 15 fabric to the roof, wall or other part of a structure to which the same is to be applied.

Another object of my invention is to provide 20 such means which may be located wholly within the substantially cylindrical or other shaped cavity of the roll of construction material and which may be positioned at any point intermediate the ends of the roll without necessitating the provision 25 of separate or special means for closing the ends of the roll. If desired, the retainer member of my invention may be so fashioned as to be of substantially the same length as the roll of construction material, 30 but preferably is substantially shorter than the roll, and may be ten inches in length, for example. These objects and other objects subsequently to be enumerated are attained 35 by providing a retainer member for the roll consisting of two end members of slightly smaller size than the inner diameter of the cavity in the roll of construction material. The end members are connected to side 40 spring or tension members whose greatest transverse distance apart is larger than the inner diameter of the cavity in the roll. Accordingly, when the retainer member is inserted into the cavity of the roll the spring members, which may be two or more 45 in number, exert a pressure against the inner wall of the cavity and thereby serve to locate and position the retainer member within the roll. In inserting the retainer member into the roll the packages of cement, nails, etc., may be placed within the spring members and between the end members which serve as stops to prevent such packages 50 from dropping out of the roll or any undesired movement within the roll.

Referring to the drawing wherein I have

illustrated a preferred form of my invention:

Figure 1 is a cross-sectional view showing a portion of a roll of construction material with the retainer member, which is the object of my invention, applied within the same and positioning the receptacles of nails, cement, etc., above referred to.

Fig. 2 is an end elevation of the same.

Fig. 3 is a side elevation of the retainer member before insertion.

Fig. 4 is a detail view of a modification.

Figs. 5 and 6 are cross-sectional and end-elevational views respectively showing still another modification of my invention.

The roll of construction material A which is generally wound in convolutions so as to give the same a substantially cylindrical form has within the same a hollow cavity or opening B generally of cylindrical form. 75 Within the cavity B is positioned the retainer member C. This member comprises the spring or tension members 1, 1 which may be made of wire or ribbon and of material having the property of being spring-like, such as steel wire, so as to exert the necessary tension against the inner wall of the roll when the member is in position. The ends of the spring members 1, 1 are turned into and held in place in slots or 80 small cavities provided in the end members 2, 2. In Fig. 2 I have illustrated in detail one way of positioning the ends of the spring members. As shown in this figure the sides of the end members at substantially diametrically opposite points are provided with slots or cavities 3, 3 into which the bent ends 5, 5 of the spring members 1, 1 are inserted. The end members are 85 slightly smaller than the diameter of the cavity B. The transverse distance apart of the spring members 1, 1 is substantially greater than the inner diameter of the cavity of the roll. Accordingly, when the retainer member is inserted in the cavity B 100 the end members just barely pass into the cavity, while the springs are put under considerable compression when the retainer is inserted into the cavity. The compression just referred to, the degree of which may 105 be varied at will by choosing the proper transverse distance apart of the spring members 1, 1, and the strength of the material of which the spring members are made, serves to locate and position the retainer 110

inside the roll in any position relative to the ends of the cavity which may be deemed desirable. If desired, the retainer member may be of such length that the outer ends 5 of the end members are substantially flush with the outer ends of the roll, or, preferably, the retainer may be considerably shorter so that the same is entirely within and clear of the ends of the roll. When 10 the retainer is being inserted into the cavity in the roll the receptacles D, D are slipped in between the end members and within the spring members, so that when the retainer is finally within the roll the receptacles D, D 15 containing the cement, nails, etc., commonly designated "trimmings" are securely located and positioned within the roll and are prevented from moving about by being limited in their movement by the end members 2, 2. 20 By my invention I am enabled to provide a simple, effective and economical means for securely positioning and locating the receptacles of construction materials to be used in the application of the roll of roofing 25 fabric or other construction material. It is obvious, also, that instead of the specific tension members shown by me, I may employ any desired or suitable tension members for exerting the necessary side or lateral 30 pressure against the walls of the cavity to position the retainer member.

In Fig. 4 I have illustrated a slight modification of my retainer member. In this modification the lateral tension members 1' 35 do not have their ends bent, but said tension members enter substantially straight slots 3' in the end member 2'.

In Figs. 5 and 6 I have illustrated a further modification of my retainer member, 40 wherein the end members 2'', of which but one is shown in the drawing, are each provided with the lateral tension members 1'', having the bent ends 5'' fitting into the slots 3'' in the indented portions 4'' of the end 45 members 2''.

Other arrangements may suggest themselves to those skilled in the art, and all such modifications, as those wherein but one tension member or more than two such members 50 are employed, are intended to be covered by the terms of the annexed claims, where the claims may be so construed.

What I claim is:

1. A retainer member for a roll of construction material, comprising two end members of smaller size than the inner diameter of the roll, and a plurality of lateral tension members connecting the end members and having the greatest transverse distance between them greater than the inner diameter of the roll, whereby when the retainer member is inserted in the roll the lateral tension members serve to position the retainer member within the roll. 60

2. A retainer member for a roll of con-

struction material, comprising two end members of smaller size than the inner diameter of the roll, and a plurality of bowed tension members connected to the end members and having the transverse distance between them greater than the inner diameter of the roll, whereby when the retainer member is inserted in the roll the bowed tension members serve to position the retainer member within the roll. 70

3. A retainer member for a hollow roll of construction material, comprising rigid and resilient elements, said member being shorter than the roll, and said resilient elements connecting said rigid elements and serving 80 to retain said member wholly within said hollow roll by frictional engagement. 75

4. A retainer member for a hollow roll of construction material, comprising a comparatively stiff member and resilient members fixedly connected to said stiff member, said resilient members projecting a substantial distance beyond said stiff member in an axial direction and having portions spaced apart to hold said retainer member in the 90 roll. 85

5. In a retainer for a roll of construction material, an end member of smaller size than the inner diameter of the roll, lateral bowed members rigidly connected to said end member and having portions flexibly held at a greater distance apart than the diameter of the roll whereby the retainer may be removably held in the roll. 95

6. In a retainer member for a roll of construction material, a portion upon which a box of "trimmings" may rest, said portion being smaller than the inner diameter of the roll, and a portion made of a resilient material rigidly connected to said first named portion and extending axially a substantial distance beyond said first named portion and so adjusted that the retainer is thereby removably held in the roll. 100

7. A retainer member for a roll of construction material, comprising two end members of smaller size than the inner diameter of the roll, and a plurality of metallic strips connecting the end members and having the greatest transverse distance between them greater than the inner diameter of the roll, whereby when the retainer member is inserted in the roll the metallic strips serve to position the retainer member within the roll. 115

8. A retainer member for a roll of construction material, comprising two end members of wood of smaller size than the inner diameter of the roll, and a plurality of wires connected to the end members and having the greatest transverse distance between them greater than the inner diameter of the roll, whereby when the retainer member is inserted in the roll the wires serve to position the retainer member within the roll. 120

125

9. A retainer member for a roll of roofing paper comprising a transverse end section and two lateral bent sections of springy material connected to said end section and projecting forwardly therefrom in an axial direction, portions of said lateral sections being spaced from each other a distance greater than any dimension of said end section.
10. 10. The combination of a roll of roofing paper having a substantially cylindrical cavity therein, and a retainer member within said cavity, said retainer member comprising a transverse end portion, and lateral outwardly bent side sections of springy material connected to said portion, said end portion serving as a stop for the packages of "trimmings" used in applying the material of the roll, and the lateral sections being spaced transversely a greater distance apart than any dimension of said end portion,
- whereby when the retainer member is inserted within said cavity the lateral sections exert pressure against the walls of the cavity and thereby function to position the retainer member within said cavity. 25
11. In combination, a roll of roofing paper having a cylindrical cavity therein, a retainer member having an end portion, and lateral outwardly bent sections connected 30 to said end portion and having their maximum transverse distance apart greater than any dimension of said end portion, whereby when the retainer member is inserted into the cavity the lateral sections will be compressed and will serve to position the retainer member within the cavity, and one or more containers within the retainer member for containing the "trimmings" used in applying the roll. 35

In testimony whereof I affix my signature.
CURTIS J. ROTHERMEL.
